Specification of Letters Patent. Patented Aug. 31, 1920.

Application filed May 19, 1914. Serial No. 839,639.

To all whom it may concern:

Be it known that I, BAPTISTE HILBERT, a citizen of the United States, residing at Worcester, in the county of Worcester and 5 Commonwealth of Massachusetts, have invented a new and useful Improvement in Looms, of which the following, together with the accompanying drawings, is a specification.

10 The present invention relates particularly to carpet looms and is embodied in a new and improved shedding mechanism therefor. In the following specification, I have described such a mechanism adapted 15 to produce a closed shed, and have illustrated such a mechanism in the accompanying drawings, but it will be apparent that my invention is not limited to a closed shed loom but is equally applicable to an open 20 shed loom.

Referring to the accompanying drawings, Figure 1 is a side view of the shedding mechanism of a loom embodying my invention, showing the parts in the positions assumed when the shed is closed.

25 Fig. 2 is a vertical longitudinal sectional view of the mechanism shown in Fig. 1, showing the parts in the positions assumed when the shed is open.

30 Fig. 3 is a top plan view of the mechanism, showing the parts in the positions assumed when the shed is open.

Fig. 4 is a detail view, in plan, of a portion of the mechanism, and

35 Fig. 5 is an enlarged side view of one of the fastening devices for holding the harness straps.

Like reference characters refer to like parts in the different figures.

40 The numerals 1, 1 denote the longitudinal arches of the head of a loom, in which the shedding mechanism is supported. The arches 1, 1 have journaled therein the transverse shaft 2, which has loosely journaled 45 thereon a bevel gear 3. The bevel gear 3 meshes with a bevel gear 4 carried upon the end of a vertical shaft 5 which is operatively connected, by mechanism which is not herein shown, with any one of the constantly 50 rotating shafts of the loom, preferably the crank shaft. The bevel gear 3 is connected at will with the transverse driving shaft 2 by means of clutch teeth upon the hub of said bevel gear which coöperate with clutch

teeth formed on a sliding clutch collar 6, 55 which is splined to the shaft 2, as shown in Fig. 4. The clutch collar 6 is engaged by a fork 7 attached to a sliding rod 8, as shown in Fig. 4. The sliding rod 8 has an attached collar 9, with a spiral spring 10 between said collar 9 and the adjacent arch 1, by which the clutch teeth on the collar 6 are normally held in engagement with the clutch teeth on the gear 3. When it is desired to disconnect the shaft 2 from the driving power, the rod 65 8 is drawn in the direction of the arrow A by the knob 11 on the outer end thereof, and the free end of the pivoted lever 12, carried on the framework, is inserted in the space between said knob and the framework, thereby 70 holding the sliding clutch collar 6 out of engagement with the gear 3, and against the tension of the spring 10.

The shaft 2 carries on its end a disk 14, 75 which has an eccentric crank pin 15 projecting therefrom. A connecting rod 16 has one end pivotally connected to said crank pin, and the other end pivotally connected to a pin 17 projecting outwardly from a longitudinally 80 slidable rack bar 18, supported in a guideway 19 and preferably resting upon a suitable roll 19'. The rack bar 18 is provided on its upper edge with rack teeth 20, adapted upon reciprocation of said bar to impart an oscillatory movement to a transverse 85 shaft 21, by means of a pinion 22 secured on the end of said shaft and having teeth coöperating with said rack teeth 20.

Above the pinion 22 is a rack 27 which is held in engagement with the pinion 22 by a flanged roll 27^a carried upon a stud held in the framework. Racks 24 and 28, Fig. 3, are duplicates on the opposite side of the loom of racks 18 and 27, and said racks 24 and 28 engage a pinion, not shown, which is 95 the duplicate of pinion 22 and carried on the opposite end of the shaft 21. The rack 28 is held in engagement with its actuating pinion by a flanged roll 28^a, Fig. 3, similar to the roll 27^a. The racks 18 and 24 have extending from their ends adjustable rods 26, and the racks 27 and 28 have similar rods 29. Each pair of rods 26 and 29 carry at their outer ends screw threaded adjustable members 30, to which are attached by bolts 31 the upper and lower knife bars 32 and 33. Each knife bar extends transversely of the framework, passing through elongated slots 34

and 35, respectively, formed in the arch members 1, 1.

- A rod 36, extending transversely between the arch members 1, 1, carries loosely thereon a series of fingers 37, the free ends of which are adapted to rest either upon the bars 38 or the rolls 39 of a pattern chain 40, as determined by the position of said chain. Each finger 37 supports on its upper edge, 10 near its free end, one end of a sliding jack rack 41, four of the latter being shown in the present instance. Each jack rack 41 has a notch 42 formed in its upper edge, for engagement by the upper knife bar 32, and a notch 43 in its lower edge for engagement by the lower knife bar 33. The operation of said knife bars in effecting the reciprocation of said jack racks is as follows:—Whenever the finger 37 of any jack rack 41 rests upon 15 a bar 38 of the pattern chain, said jack rack is lowered so as to have its lower notch 43 in position to be engaged by the lower knife bar 33, but its upper notch 42 is thereby removed from the path of movement of the 20 upper knife bar 32. The movement of lower knife bar 33 to the left effects a movement of the jack rack in the same direction (see Fig. 2), but on the return movement of said knife bar, there is no motion imparted to the 25 jack rack by reason of the disengagement of the knife bar with the notch. To provide for the return of the jack rack, the lower knife bar has connected thereto a pair of forwardly extending members 44, which are 30 screw threaded on their outer ends and connected by a bar 45 adjustably held between nuts 46 on either side. Upon movement of the knife bar 33 to the right, this bar 45 engages the forward end of aforesaid jack rack 41, and also any of the other jack racks which are in a similar forward position, to 35 return the same to the position shown in Fig. 1. When the finger 37 of any jack rack is lifted by the roll 39 of the pattern chain, 40 said jack rack is thereby lifted clear of the lower knife bar 33, and the upper notch 42 of said jack rack is brought into the path of movement of the upper knife bar 32, as shown in Fig. 2, so that the movement of 45 said knife bar to the right carries said jack rack to the right. The said jack rack is returned to its central position by the engagement with its rear end of the bar 47, carried, similarly to the bar 45, on rearwardly 50 extending members 48 supported by the upper knife bar.
- Each jack rack 41 has rack teeth 50 formed on its upper edge. A fixed shaft 51 has loosely journaled thereon a series of segmental gears 52, one for each jack rack, and the teeth of said gears mesh with the rack teeth on the respective jack racks so that the movement of said jack racks is utilized to impart oscillatory movement to said gears. 55 The jack racks are held in engagement with

the gears 52 by rolls on a shaft 41^a directly beneath the shaft 51. Each gear 52 is provided with a crank arm 53 having two or more holes in its outer end to provide for the pivotal connection thereto of a curved link 54, by which said arm is connected with the upright arm of a harness jack 55, pivoted on a shaft 56, which forms the pivotal support for a series of such harness jacks, in the present instance four in number, to correspond with the number of jack racks and harness frames. Each harness jack 55 is adapted for the actuation of one of the harness frames 57 of the loom. To this end each harness frame 57 has secured to its upper side one or more fastening devices 58, one of which is shown, enlarged, in Fig. 5. The fastening device comprises a substantially flat oval frame, provided on one end with a cylindrical boss 59 having a longitudinal aperture opening into the space enclosed by said frame. A rod 60 passes loosely through said aperture, being provided on its inner end with a screw thread to receive a pair of adjusting nuts 61. At its outer end said rod 60 is flattened, and is split a short distance longitudinally to provide for the insertion of the end of the harness strap 62, which, in the present instance, takes the form of a flat steel ribbon, the end 90 of which is securely riveted in place. A compressed spiral spring 63 encircling said rod 60 has one end firmly secured to the end of said rod and the other end firmly secured to the boss 59. In Fig. 1 I have shown two 100 fastening devices suitably secured to the upper side of one of the harness frames 57. The strap 62 from one of said devices is carried over a pulley 64, and the strap from the other is carried over a pulley 65 and under the pulley 64, both of said pulleys being journaled on fixed shafts carried between the arches. Said straps are joined together beyond said pulleys and attached to a common fastening device 66, similar in all respects to the fastening device 58, Fig. 5. Each fastening device 66 is adapted to have its end pivotally attached to the upper end of the corresponding harness jack 55, the latter being provided with a series of holes 110 67 whereby the distance of said connection from the pivotal center of said jack may be varied, to vary the movement of the harness frame as desired. Each harness frame is connected in the usual and well known manner with the opposite or lower ends of the harness jacks 55. When the harness frames have been attached to their respective harness jacks, any lost motion may be taken up and the strap connections drawn taut by 125 screwing up the nuts 61 and drawing the rods 60 through the bosses 59, against the tension of the springs 63.

The pattern chain 40 is supported upon a rotating barrel 68, carried upon a shaft 69 130

and driven from the shaft 2 by means of intermeshing gears 70 and 71 carried by said shafts. The shaft 69 of the pattern chain can be rotated by hand to set the pattern chain by disconnecting the shaft 2 from the driving power and rotating it by means of the hand wheel 72, Fig. 4.

The mechanism above described for imparting motion to the harness frames of the loom presents many advantages over the shedding mechanisms heretofore employed. The knife bars, instead of being actuated by links attached to the ends of a rocking arm as is usual in looms of this class, are driven by the rack bars which derive their reciprocation directly from a crank on the shaft 2, and are constrained to move in parallel planes, thereby insuring a smooth and uniform motion for said knives. Also the motion of the knives is imparted to the harness jacks by means of racks, so that the jerks and strains which are common to other types of harness motions are effectually eliminated. The period of dwell of the harness frames in the open position of the shed may be determined to a nicety by the longitudinal adjustment of the bars 45 and 47 on their respective supporting members 44 and 48, as will be readily apparent. The curved links 54 allow the crank arms 53 to pass below the centers of the gears at each oscillation of the gears. The provision of a plurality of pivot holes for connecting the links to the gears furnishes a means for adjusting the throw of the harness frames, as does also the provision of the series of pivot holes in the ends of the harness jacks.

The fingers 37 interposed between the pattern chain and the several jack racks, insure a firm and extended bearing for the edges of said racks, which is superior to the supporting of said racks directly upon the bars and rolls of the chain.

The employment of steel ribbons, in lieu of the leather straps ordinarily used for connecting the harness frames to the harness jacks, provides connections which are entirely free from stretching and, consequently, the need for frequent adjustment is eliminated. The fastening devices 58 and 66 furnish a ready means of adjustment, by taking up on the nuts 61. Furthermore, the springs 63 serve to eliminate all lost motion or jar in the harness frames when the direction of movement of the latter is changing.

While I have shown and described a harness motion for a closed shed loom, it will be obvious that my invention is not limited to such, but may be employed with equally advantageous results in an open shed loom. The differences in construction and operation of the latter type over the former do not affect the essential elements of the present invention.

The operation of the mechanism above described is as follows:—The rotation of shaft 2 and crank disk 14 will impart a reciprocating motion to the knife bars 32 and 33 by means of their interposed gears, moving them from a central position as shown in Fig. 1, when the shed is closed, to the positions shown in Fig. 2, when the shed is open. At each movement of the knife bars into their central position, the jack racks which have been previously moved into the positions shown in Fig. 3, are pushed into a central position by the bars 45 and 47. At the next movement of the knife bars from the position shown in Fig. 1 to that shown in Figs. 2 and 3, the jack racks which have been raised by the pattern chain are engaged by the upper knife bar 32, and those which have not been raised will be engaged by the lower knife bar 33, causing all the warp threads to be either raised or lowered and forming an opened shed. The notches 42 and 43 of the jack racks engaged by the knife bars are slightly undercut to fit the beveled edge of the knife bars, and the pushing bars 45 and 47 are spaced a slight distance from the ends of the jack racks with which they contact, in order to enable the knife bar to move slightly and release its engaged jack rack before the contact of the pushing bar. This provides a more secure engagement by the knife bars and the lost motion of the pushing bars 45 and 47 is not sufficient to prevent the practical closing of the shed.

I claim:

1. In a loom shedding mechanism, a pair of horizontally reciprocating rack bars on opposite sides of the machine, a crank journaled substantially in the plane of and operatively connected with one of said rack bars, means for continuously rotating said crank, a shaft extending transversely across the machine between said rack bars, gears attached to the opposite ends of said shaft engaging said rack bars, upper and lower knife bars adjustably attached to said rack bars, jack racks engaging said knife bars to move the jack racks in either direction from a central position, and means for returning the jack bars to a central position independently of their engagement by the knife bars.

2. In a loom shedding mechanism, a series of jack racks operatively connected with the harness frames of a loom, an upper and a lower knife bar, means for reciprocating said knife bars toward and away from a central position, means for engaging said jack racks by said knife bars to move the former in either direction from a central position, and means for returning said jack racks to a central position independently of their engagement with said knife bars.

3. In a loom shedding mechanism, a series of jack racks, an upper and a lower knife bar, means for reciprocating the knife bars in opposite directions to and from a central position, undercut notches on said jack racks for engaging said knife bars, bars abutting the ends of said jack racks to return the jack racks to a central position, said abutting bars being spaced from the jack racks to permit the release of their undercut notches from the knife bars, and means for moving said abutting bars to return the jack racks to their central position.
4. In a loom shedding mechanism, a series of jack racks, reciprocating knife bars for moving said jack racks in opposite directions from a central position, means for actuating said knife bars, bars attached to said knife bars and arranged to abut against the ends

of said jack racks and return them to a central position.

5. In a loom shedding mechanism, a series of slidable jack racks lying in the same horizontal plane, upper and lower reciprocating knife bars, means for reciprocating said knife bars in opposite directions, means for engaging said knife bars with said jack racks to move the latter in one direction, and a pair of bars adjustably connected with said knife bars for reversing the movement of said jack racks, when said knife bars are reversed in movement.

Dated this fifteenth day of May, 1914.

BAPTISTE HILBERT.
